CLAIM

The ornamental design for a portable power supply, as shown and described.

DESCRIPTION

FIG. 1 is a top, front, left perspective view of a portable power supply, showing our design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof; and,

FIG. 8 is a perspective view of the portable power supply with the handle in an unfolded position.

The broken lines shown in the drawings are for the purpose of illustrating portions of the portable power supply that form no part of the claimed design.

1 Claim, 8 Drawing Sheets(56)
